REFRIGERATED DISPLAY CASE FOR PREPARED FOODS OR THE LIKE

Eugene E. Goodrich, Park Ridge, and Joseph R. Mango,
Midlothian, Ill., assignors to Bastion-Blessing Company,
Chicago, Ill., a corporation of Illinois

Filed Aug. 25, 1960, Ser. No. 61,880

Term of patent 14 years

(Cl. D80—11)

FIG. 1

FIG. 2

FIG. 3

FIG. 5

FIG. 1 is an enlarged front perspective view of a refrigerated display case for prepared food or the like embodying our new design;

FIG. 2 is an end elevational view of our design, opposite end being substantially a mirror image thereof;

FIG. 3 is a rear elevational view of our design;

FIG. 4 is a top plan view of our design; and

FIG. 5 is a bottom plan view of our design.

The characteristic features of our design reside in the tilted rear mirror in association with the particular front essentially as shown.

We claim:

The ornamental design for a refrigerated display case for prepared food or the like, as shown and described.
